(57) **CLAIM**

The ornamental design for an inner insert for pneumatic tyre as shown and described.

DESCRIPTION

1. Inner insert for pneumatic tyre

1.1 : Perspective

1.2 : Left

1.3 : Right

1.4 : Front

1.5 : Back

1.6 : Cross sectional

FIG. 1.1 is a perspective view of the design; fig. 1.2 is a left view thereof; fig. 1.3 is a right view thereof; fig. 1.4 is a front view thereof; fig. 1.5 is a back view thereof; fig. 1.6 is a cross-sectional view taken along line 6-6 of fig. 1.3.

1 Claim, 6 Drawing Sheets
